MARTIN EKENBERG, OF STOCKHOLM, SWEDEN, ASSIGNOR TO MARTIN EKENBERGS AKTIEBOLAG, OF STOCKHOLM, SWEDEN.

DRUM FOR VACUUM-PANS.

SPECIFICATION forming part of Letters Patent No. 727,317, dated May 5, 1903.

Application filed October 22, 1902. Serial No. 128,224. (No model.)

To all whom it may concern:

Be it known that I, MARTIN EKENBERG, a subject of the King of Sweden and Norway, and a resident of Stockholm, Sweden, have 5 invented certain new and useful Improvements in Drums for Vacuum-Pans, of which the following is a specification.

This invention relates to a vacuum evaporating apparatus; and the object is in part to 10 produce an especially light drum having an extended evaporating-surface and in part to improve the means for utilizing the heating medium or fluid.

In the accompanying drawings, which serve 15 to illustrate an embodiment of the invention, Figure 1 is a longitudinal vertical mid-section of the apparatus, and Fig. 2 is a vertical transverse section of same at line x^2 in Fig. 1.

20 In the drawings, 1 designates a vacuum-pan. 2 designates the pipe for supplying thereto a liquid L to be evaporated, and 3 designates the outlet-pipe for the vapors, to be drawn off by a pump or the like. (Not shown.) With- 25 in the chamber in the pan is rotatively mounted a hollow shaft 7, which carries a drum of peculiar construction. This drum is essentially hollow and consists of two end plates 6, which are fixed on the shaft 7 and at their outer margins are rigidly connected to inner cylindrical plates 5, which are secured at their respective ends (see at y in Fig. 1) to an outer cylindrical plate 4, thus forming an annular cylindrical space be- 30 tween the plates 4 and 5. The said annular space is divided by a circumferentially-dis- 35 posed cylindrical baffle-plate 12, which is carried by a plurality of tubular radial spokes or arms 11.

40 The tubular shaft 7 is in two alined parts or sections, which are connected within the drum or between the end plates 6 by a hollow hub 8, in which are set the tubular spokes or arms 11, and in this hub is a cross- 45 partition 9 and a port or ports or apertures 10, situated at one side of said partition, which apertures open into the hollow of the drum between the end plates 6.

The object is to heat the outer face of the 50 drum formed by the plate 4 uniformly, and to effect this object the vapor or heating me-

dium enters the hollow shaft 7 at the left in Fig. 1 and flows (see arrows) from the said shaft through the ports 10 into the drum and out to the annular space between the plates 4 and 5. The baffle-plate 12 compels the fluid medium to flow laterally and around its ends into the space between the plates 4 and 12, thence it flows back to the points where the hollow arms 11 open through the baffle-plate 12, thence it flows inward radially through said arms as ducts to the hollow of the hub 8 at the outlet side of the partition 9, and thence out through the section of the shaft 7. (Seen at the right in Fig. 1.) Thus a continuous circulation of the heating fluid or medium is effected in a manner to uniformly heat the plate 4 of the drum.

Preferably the end plates will be concave exteriorly.

The arms or spokes 11 serve the purpose of carrying the baffle-plate 12 and also as radial ducts.

The rotating drum dips into the liquid L to be evaporated, and as it rotates the partially-dried film formed on its surface is removed by a scraper 13 and falls into a receptacle 14. The vapors resulting from the evaporation are drawn off at 3 in a known way, and any liquid carried over and condensed flows back into the pan at an inlet 15.

The arrangement described, where the heating medium enters at the left in Fig. 1, tends to heat the end plates 6 and inner plate 5 to a higher temperature than the plate 4, which may be in some cases advantageous; but if it be desired to reverse these conditions and to heat the plate 4 to a higher temperature than the other parts of the drum the heating medium may be admitted at the opposite end of the shaft 7, so as to reverse the flow. The drum may be driven by an ordinary belt and pulley. (Not shown.)

The vacuum-pan itself, with the exhausting devices, the scraper 13, and receptacle 14, possesses no novel features so far as this application is concerned.

Having thus described my invention, I claim—

1. In an apparatus for the purpose specified, the combination with the vacuum-pan, of the sectional tubular shaft rotatively

mounted therein, the hollow drum mounted on and carried by said shaft, said drum having a hollow, annular space in its rim, a baffle-plate of cylindrical form in and dividing the said annular space, ports leading from one section of said tubular shaft to the annular space at the inner side of the baffle-plate, and ducts connecting the other section of said shaft with the annular space at the outer side of said baffle-plate, substantially as and for the purpose set forth.

2. In an apparatus for the purpose specified, the combination with the vacuum-pan, of the tubular shaft rotatively mounted there-in, said shaft being in two alined sections, the hollow hub connecting said sections, said hub having in it a partition 9 and an aperture or port 10 at one side of said partition, the hollow drum mounted on and carried by said

shaft and inclosing said hub, whereby the 20 ports 10 open into the hollow of the drum, the baffle-plate 12, of cylindrical form, in an annular space in the drum near its periphery, and the radially-disposed tubular arms 11, connecting said baffle-plate with said hub 25 and connecting also the space in the drum exterior to said baffle-plate with the hollow in the hub at the side of the partition therein opposite to the ports 10, substantially as and for the purposes set forth.

In witness whereof I have hereunto signed my name in the presence of two subscribing witnesses.

MARTIN EKENBERG.
